CLAIM

The ornamental design for a traction motor boot mount as shown and described.

DESCRIPTION

FIG. 1 is a top-front perspective view of a traction motor boot mount according to an embodiment of the claimed design.

FIG. 2 is a bottom-rear perspective view of the traction motor boot mount of FIG. 1.

FIG. 3 is a top view of the traction motor boot mount of FIG. 1.

FIG. 4 is a bottom view of the traction motor boot mount of FIG. 1.

FIG. 5 is a front view of the traction motor boot mount of FIG. 1.

FIG. 6 is a rear view of the traction motor boot mount of FIG. 1.

FIG. 7 is a right side view of the traction motor boot mount of FIG. 1.

FIG. 8 is a left side view of the traction motor boot mount of FIG. 1.

FIG. 9 is a top-front perspective view of the traction motor boot mount of FIG. 1 in a use environment; and,

FIG. 10 is a sectional perspective view of the traction motor boot mount of FIG. 1, in the use environment of FIG. 9, taken along line 10-10 in FIG. 9.

The dash-dash broken lines in the drawings and the oblique broken line hatch shading in FIG. 10 of the drawings illustrate environmental subject matter that forms no part of the claimed design.

The dash-dot-dash broken lines in FIG. 9 form no part of the claimed design.
